FLUID DISPLACEMENT MECHANISM

Jesse W. Forrester, Marshfield, and James V. Sheridan, Powers, Oreg.

Application September 19, 1938, Serial No. 230,632

7 Claims. (Cl. 230—187)

Our invention relates to fluid displacement mechanisms, and particularly to air compressors, having a plurality (two or more) of fixed piston-operated fluid-displacement or compressor units radially disposed about a driving cam, and bell crank piston-return mechanisms adapted to lower one piston as the next piston is raised by the cam.

An object of our invention is to provide a compressor having large capacity, small size for said capacity, and rugged simplicity. Other objectives will be apparent as we proceed.

Fig. 1, of the accompanying drawings, is a plan view showing an eight unit compressor; Fig. 2 is a side view; Fig. 3 is a section on 3—3 of Fig. 1; Fig. 4 is a section on 4—4 of Fig. 2; Fig. 5 is a side view of the piston-return mechanism shown in Fig. 4; Fig. 6 is a partial section cut as shown in Fig. 4, but showing another form of piston-return mechanism; Fig. 7 shows another piston-return mechanism; Fig. 8 is a plan view of the piston-return mechanism shown in Fig. 7, with one of the arms provided with adjustment; Fig. 9 is a side view of Fig. 8; Fig. 10 is a plan view of the piston valve; Fig. 11 is a plan view of the valves in the cylinder head; Fig. 12 is a section on 12—12 of Fig. 11; Fig. 13 is a section on 13—13 of Fig. 11.

Throughout the drawings and the specification similar numerals refer to similar parts.

The increased use of air, especially in the field, has opened up a market for a simple and rugged machine that has a large capacity for its size, and that is cheap to build, keep up, and service. The compressor shown in Figs. 1, 2, 3, and 4, may be equipped with the other piston-return mechanisms shown and described, also, it may be equipped with other types of valves, none being shown.

The major portion of the compressor base 1 is frusto-conically shaped interiorly and exteriorly, with its upper end merged into a cylindrical neck 2 and its lower end into a cylindrical base 3 pierced by the holes 4 thru which the means used to secure the compressor to its support may be passed. The neck 2 is bored for the reception of the snugly fitting boss 5 formed below the outstanding shoulder-forming flange 6 on the cylindrical barrel portion 7 which depends from the lower cover 8 of the cam chamber casing 9. The flange 6 gives support to the lower cover 8 directly and indirectly to the cam chamber casing 9, and thru it are passed the cap screws 10 by means of which said cover is secured to the neck 2 of the base 1. The cylinder

cam chamber casing 9 is bored top and bottom concentrically for the reception of the snugly fitting bosses 11 and 12 formed beyond the outstanding shoulder-forming flanges 13 and 14 on the lower cover 8 and the upper cover 15 respectively. The cap screws 16 and 17, respectively, pass thru the flanges 13 and 14 and into the cylindrical cam chamber casing 9 and thereby secure the covers 8 and 15 to said casing. The peripheral face 18 of the casing 9 is bored radially for the reception of the snugly fitting boss 19 formed on each cylinder 20. The boss 19 is in reality an extension of the cylindrical wall 21 of the cylinder 20 beyond the outstanding shoulder-forming flange 22 thru which is passed the stud bolts 23 by means of which the cylinders 20 are secured to the casing 9. Within each cylinder is a piston 24 provided with a plurality of sealing rings 25 and reciprocable within said cylinder thru the agency of the connecting rod 26 hingedly secured to said piston by the wrist pin 27 which is press fitted therein and free to turn in the bearings 28 provided in the bosses 29 on the piston wall 30. The connecting rod 26 is bifurcated to straddle a roller bearing 31 of the non-separable straight-roller type whose inner race 32 is a push fit on the lower wrist pin 33 and further confined thereon by the inwardly extending boss 34 on the hub 35 of each leg 26A of the connecting rod, and whose outer race 36 is free to rotate. The hub 35 also has an outwardly extending boss 37 to provide adequate bearing area on the wrist pin 33 for the loads that may come upon the connecting rod and to provide a pintle bearing for one end of the radius link 38. The hub 38A on the opposite end of each radius link is push fitted upon the hinge pin 39 supported by the bearings 40 in opposed bosses 41 on the upper and lower covers 15 and 8. Also push fitted upon the same hinge pin 39 is the hub 42 of a double quadrant gear 43. After assembling the parts shown in Fig. 4, we believe that it is best to weld each pair of the hubs 38A together or to detachably connect them by such means as a right and left hand nut (not shown), and to weld the section 43A of the quadrant gear to the adjacent radius link 38 or to detachably connect them by such means as bolts (not shown). A review of Fig. 5, will show a balanced mechanism which, although it involves a duplication of some members, will in the end pay large dividends in the way of trouble-free hours.

Movement is imparted to the above described mechanism thru the lobes 44 on the cam 45

which is indicated as rotating clockwise. When the lobe 44 engages the outer race of the roller bearing 31, which we will henceforth refer to as a roller, the roller is raised and with it the piston 24 to compress the charge of air ahead of it. The path of the roller is guided and fixed by the radius links 38 which, being secured to the sections 43A of the double quadrant gear 43, raises this section with them. Since both of the sections 43A and 43B are integral and angularly disposed, the section 43B moves down as the section 43A moves up, and since section 43A of one quadrant gear meshes with the section 43B of the adjacent quadrant gear, and vice versa, adjacent pistons on each side will reach their lowest point as the intermediate piston reaches the highest point as clearly shown in Fig. 4. A perusal of Fig. 4, shows that by having the radius links hinged to the left of a roller, 10 when the direction of rotation of the cam is clockwise, each roller 31 will be raised in the direction of rotation and not against it.

The above bell crank piston-return mechanism is, we believe, an improvement over the one 25 shown in Fig. 6, in which a bell crank of the conventional type is shown. Although this mechanism is more simple and requires but one bell crank to two cylinders, it causes one roll 31 to be lifted with and the other against the direction of cam rotation. In this instance, the double quadrant gear, which constitutes a bell crank, is eliminated and a pair of radius links 38B are joined integrally with the hub 38A and the radius links 38 to form a double arm bell crank. 30 In the arrangement the same hinge pin 39, wrist pin 33, roll 31, and connecting rod 26, are used and mounted as previously described.

The inherent disadvantage in the above mechanism may be overcome in a very simple manner as shown in Fig. 7, by slotting the end of the radius links 38B to form the jaws 46 adapted to straddle an extended wrist pin 33 or a pin carried by said wrist pin as we have shown. The wrist pin 33 is made hollow for the reception 45 of a pintle pin 47 which has its projecting ends flattened to provide parallel bearing surfaces 48 for engagement of the jaws 46 over which said jaws may slide, and the shoulders 49 for retaining the pintle pin 47 within the wrist pin 33. The pintle pin 47 is made a snug turnable fit 50 within the wrist pin so that it may adjust itself to the radial movement of the radius links 38B. The combination of the jaws and pintle pin takes the place of the teeth 43C on the double quadrant gear 43 and a sliding action is substituted for the rolling action of the gear teeth. In this instance, it is necessary to provide one bell crank for each cylinder since the slotted links 38B of one bell crank engage the pintle pin 47 of the preceding bell crank and hence all 55 of the rolls 31 are raised in the direction of cam rotation.

The piston-return mechanisms so far described must be accurately constructed in order for them 60 to function in the most efficient manner. Accurate work brings up the cost of manufacture and to keep this down two different means have been shown. In Fig. 4, the side 44A of the cam lobe 44 has been relieved, and in Fig. 8, the slotted 65 radius links 38B have been made in two sections hingedly connected together, with their relative movement limited and cushioned. The hub section 50 is formed with two knuckles 51 and the jaw section 52 with three knuckles 53. Thru 70 these knuckles the hinge pin 54 is passed, the

same being a snug fit in the knuckles but adapted to be removed by engaging its head 54A. Compression springs 55 to take the normal load coming on the section 52 are inserted between the two sections 50 and 52 to cause the roller 31 5 to always remain in contact with the cam surface 45A whereby the cam lobe 44 does not have to be relieved to compensate for lack of exacting workmanship. A further advantage is the absence of shock or noise when the rollers are engaged by the lobes. The upward movement of the jaw section 52 is limited by the upper contacting surfaces 56, and the downward movement, which the springs 55 may effect, is limited by the lower contacting surfaces 57. It is evident 10 that both arms of the bell crank of Fig. 6, may be made adjustable.

The cam 45 is secured to the vertical drive shaft 58 supported on a double row ball bearing 59 in the cartridge 60 mounted within the 20 compressor base. The base has a diaphragm 62, positioned at the junction of the frusto-conical portion 1 with the cylindrical portion 3, provided with the boss 63 within the frusto-conical portion 1 and a boss 64 within the cylindrical 25 portion 3, both bosses being axially aligned and bored for the reception of the barrel portion 60A of the cartridge 60 whose position is fixed by the nut 65, threaded upon its exterior and against the bottom of the boss 64 thereby clamping the 30 cartridge flange 66 against the top of the boss 63. The inner race 59A of the ball bearing 59 is clamped against the hub 67 of the bevel gear 68, which in turn is clamped against a ring 69 formed on the shaft 58, by the nut 70. The 35 outer race 59B is confined between the interior shoulder 71 on the cartridge 60 by the cover plate 72. A shoulder 73 is formed on the shaft 58 adjacent the lower cover 8. The lower cover 9 is provided with an upper diaphragm 74 and a 40 lower diaphragm 75 spaced apart to form an intervening exhaust manifold 76 between them and the outer cylindrical enclosing wall 77, which forms the boss 11, and the inner cylindrical enclosing wall 78, spaced from the median line 79 45 to provide a cylindrical chamber 80 for the reception of the lower roller bearing 81, whose outer race 81A is retained between the annular shoulder 82 formed as part of the enclosing wall 78, and the cover plate 83 secured to the diaphragm 50 75 by the cap screws 84. The inner race 81B is retained between the shoulder 73 on the shaft 58 and the spacer 85 between the hub 86 on the cam 45.

The annular intake manifold 87 and the 55 cylindrical bearing chamber 88 are formed similarly. The upper cover 15 comprises the upper diaphragm 89, the lower diaphragm 90, the outer cylindrical enclosing wall 91, and the inner cylindrical enclosing wall 92 having an annular 60 shoulder 93 between which and the cover plate 94 is the outer race 95A of the roller bearing 95. The inner race 95B rests upon a spacer 96, similar to the spacer 85, supported by the hub 86 of the cam 45.

The bevel pinion 97 is the direct means of imparting movement to the bevel gear 68. This pinion is secured to the shaft 98 which is supported on its inner end by the roller bearing 99 whose inner race 99A is positioned against the 70 shoulder 100 on the shaft, and whose outer race 99B is positioned against a shoulder 101 formed on the far end of the annular bearing chamber 102 supported by the bracket 103 which extends from the walls of the lower cover 8. The 75

outer end of the shaft 98 is supported by the double row ball bearing 104 whose inner race 104A is clamped against the spacer 105, which contacts the hub of the pinion 97, by the nut 106 threaded upon the shaft 98. The outer race 104B is confined between an inner annular shoulder 107 on the bearing chamber 108 of the cartridge 109 mounted in the bearing extension 110 on the base 1 by the cover plate 111 secured to the bearing extension by the cap screws 112 which pass thru a flange 113 on the cover plate and the flange 114 on the cartridge. The cover plate 111 is provided with the conventional grease grooves 115 for the retention of lubricants within the bearing. The prime mover for the compressor may be direct connected to the shaft 98 by a flexible coupling or indirectly connected by a multiple belt drive, for instance, no method being shown.

20 Air enters the intake manifold 87 thru one or more suitable air filters 116 (two being shown) secured to the upper diaphragm 89 of the cover 15 and are removable with said cover. The air passes from the manifold 87 thru the ports 117, 25 formed in the lower diaphragm 90 adjacent each cylinder 20, into the cam chamber 9A. As a piston 24 is being brought to its lowest position by the piston-return mechanism, air within the cam chamber 9A passes thru the valve 118 in the 30 head 24A of the piston 24 into the piston chamber 20A. When the piston 24 is raised by the cam lobe 44 the air trapped within the chamber 20A is forced out thru the valves 119 in the head 20B into the valve chamber cap 120 from which it is led 35 thru the pipe 121 into the exhaust manifold 76 entering said manifold thru the outer cylindrical enclosing wall 77. Two chambers 122 communicate with the wall 77 and the interior of the manifold 76. A pipe 123 threaded into the wall 40 77 communicates with the chamber 122 and conveys air from the manifold to a receiver (not shown).

45 From the above description and with reference to the drawings, it is evident that our compressor may be readily assembled and dis-assembled in units. The drive pinion unit may be removed as such, and the top cover 15 may be lifted off to expose the cam and all the piston-return mechanisms. The compressor may be separated at the 50 junction of the lower cover 8 with the base 1, and by unscrewing the nuts 65 the whole gear assembly may be removed from the base.

55 There is always considerable heat generated during the compression of air and some of this heat is transferred thru the structural parts and given off to the air as radiated heat. Much of this heat is given off to the air within the cam chamber 9A, but in our device this heated air and the radiating medium is cooled by the cooler exterior air sucked into the cam chamber 9A and then passed on thru the cylinders 20 to the receiver. To further facilitate the dissipation of heat we also employ the well known means of 60 providing radiating fins 124 on the cylinders 24. It may also be pointed out that heat from the cylinders 20 and the pipes 121 may be further dissipated by extending the shaft 58 thru and beyond the cover plate 94 to receive a fan 125 adapted to take its air thru the cylindrical tunnel 126 formed by a sheet metal shell 127 attached to the valve chamber cap 120 and extending from the junction line of the base and lower cover 8 to above the fan blades 125A, whereby accidental 70 contact with the fan blades is prevented. The 75

fan and guard, which the tunnel shell may be called, are shown dotted in Fig. 3, only.

In order to lubricate our compressor when it is standing on the side of a hill as well as when it is working on a level street, we bring the oil to 5 the top of the shaft 58 and let it work down thru the upper roller bearing 95 onto a slightly dished disk 128 mounted on the cam hub 86, from which it is thrown by centrifugal force onto the pistons and piston-return mechanisms from which the 10 surplus oil finds its way downward thru the lower roller bearing 81 onto the top of the bevel gear 68 from which some of it works into the roller bearing 99, onto the bevel pinion 97, and along the shaft 98 into the ball bearing 104. Some of 15 the oil dropping on the gear 68 finds its way thru a small aperture 129 in the gear web and thence thru the lower ball bearing 59 into the sump 130 formed below and as a part of the cartridge chamber 60B. The major portion of the oil finds 20 its way to the sump 130 thru the apertures 131 which bleed the oil dammed up on the diaphragm 62 by the boss 63. Submerged in the sump 130 is a rotary pump of the conventional type having multiple spring-pressed impellers (not shown in 25 detail) slidably mounted in the end of the shaft 58 to maintain a contact with the interior of the impeller chamber 132 eccentric to the end of the shaft 58 which extends into said chamber. The pump casing 133 comprises a top portion 134 and 30 a cover plate 135 to which a cap 136 is secured, countersunk head screws being used but not shown to fasten the several parts together. A groove is cut in the periphery of the top casing portion 134 to form an annular collecting chamber 35 137 having communicating apertures 138 whereby oil may find its way into said chamber. An intake aperture 139 leads from the collecting chamber to the interior of the impeller chamber. Oil entering the impeller chamber is carried 40 around by the impeller blades 140 and forced out thru the discharge aperture 141 into the passage 142 in the cap 136 and up the bore 143 in the shaft 58 to begin another cycle. The pump casing is clamped against a shoulder 145 in the 45 cartridge chamber 60B by the cover plate 146 threaded upon the exterior of the cartridge 60. In clamping the casing against the shoulder, a lead washer 147 is pressed slightly against the shoulder 148 on the shaft 58 to form a seal. The 50 communicating apertures 138 are extended into communication with the settling chamber 149 formed by the cover plate 146 provided with a plug 150 for draining. Fresh oil may be placed 55 within the compressor thru the plug 151 in the cover plate 94 or the shaft 58.

While all working parts of a compressor should be well lubricated, oil in a receiver is not desirable. In the compressor illustrated all parts are balanced as to wear and lubrication, yet an 60 undesirable amount of oil cannot pass thru the valves and into the receiver.

The head 24A of each piston 24 is counterbored for the reception of a valve plate 152, secured to the head 24A by the countersunk head screws 65 153, in whose bottom face is milled spaced apart vertically arcuated grooves 154 in alignment over a series of elongated apertures 155 communicating with the grooves 154 and the interior of the hollow piston 24. The grooves 154 are somewhat wider than the diameter of the apertures 155 beneath them whereby a thin strip of spring steel constituting the valves 118 may overlap them. The space between the grooves 154 is milled entirely thru the valve plate 152 to form 70 75 76

the slots 156 which merge with adjacent grooves 154. The top of the piston chamber head 20A is counterbored for the reception of the valve plate 157, secured to the head 20A by the countersunk head screws 158, in whose bottom face is milled spaced apart vertically arcuated grooves 159 in alignment over a series of elongated apertures 160 communicating with the grooves 159 and the piston chamber 20A. These grooves 159 are also wider than the apertures 160 beneath them and for the reasons previously stated. These grooves 159 also merge with the slots 161. The slots 156 and 159 are made wider over part of their length to expose part of the valves 118 and 119. The valves 118 and 119 are free to conform to the curvature of grooves above them when acted upon by air pressure beneath them. When the piston 24 is lowered the pressure of the air within the cam chamber 9A raises the valves 118 and flows thru the apertures 155 and the slots 156 into the piston chamber 20A. When the piston is raised pressure within said chamber lowers the valves 118 and raises the valves 119 and air within the chamber is forced out thru the apertures 160 and the slots 161 on its way to the receiver. When the piston 24 starts to lower, receiver pressure acts upon the top of the valves 119 and lowers them. With this arrangement, the intake valves 118 remain open during the downward movement of the piston which makes for efficiency in any compressor.

It is readily apparent that our compressor may be changed considerably in appearance and arrangement without departing from the basic ideas embraced in our claims in which we seek to set up our ownership of all that comes fairly within their scope.

What we claim as new is:

1. A fluid displacement mechanism having in combination a plurality of fixed radially disposed fluid displacement units each unit including a cylinder, a piston slideable within it, a connecting rod having one end hingedly connected to the piston, and a cam roller associated with the free end; a centrally positioned rotatable cam to cause a piston to be moved inwardly in a cylinder to compress air within said cylinder; and a bell crank piston-return mechanism having one arm including a quadrant gear and a radius link hingedly connected to the free end of the connecting rod, and a second arm angularly disposed to the first arm and terminating in a quadrant gear adapted to mesh with the first mentioned gear of the preceding unit whereupon inward movement of the piston of one unit causes outward movement of the piston of the following unit.

2. A fluid displacement mechanism having in combination a plurality of fixed radially disposed fluid displacement units each unit including a cylinder, a piston slideable within it, a connecting rod having one end hingedly connected to the piston, and a cam roller associated with the free end; a centrally positioned rotatable cam to cause a piston to be moved inwardly in a cylinder to compress air within said cylinder; a bell crank piston-return mechanism having one arm hingedly connected to the free end of the connecting rod and a second arm angularly disposed to the first arm and terminating in a jaw having slideable connection with the free end of the connecting rod of the preceding unit whereupon inward movement of the piston of one unit causes outward movement of the piston of the following unit.

3. A fluid displacement mechanism having in combination a plurality of fixed radially disposed fluid displacement units each unit including a cylinder, a piston slideable within it, a connecting rod having one end hingedly connected to the piston, and a cam roller associated with the free end; a centrally positioned rotatable cam to cause a piston to be moved inwardly in a cylinder to compress air within said cylinder; a bell crank piston-return mechanism having one arm hingedly connected to the free end of the connecting rod and a second arm, angularly disposed to the first arm, provided with an end section having limited hinged connection thereto and terminating in a jaw having slideable and hinged connection with the free end of the connecting rod of the preceding unit whereupon inward movement of the piston of one unit causes outward movement of the piston of the following unit, and compression springs interposed between the arm and its end section to take the normal load coming on said end section.

4. A fluid displacement mechanism having in combination a plurality of fixed radially disposed fluid displacement units each unit including a cylinder, a piston slideable within it, a connecting rod having one end hingedly connected to the piston, and a cam roller associated with the free end; a centrally positioned rotatable cam to cause a piston to be moved inwardly in a cylinder to compress air within said cylinder; a bell crank piston-return mechanism comprising a bell crank having its arms formed in two sections having limited hinged connection therebetween and hingedly connected to the free end of the connecting rods of adjacent units whereupon inward movement of the piston of one unit causes outward movement of the piston in the other unit, and compression springs interposed between the arm sections to take the normal load coming on the connecting rod section.

5. A compressor having in combination a casing; a cam chamber within the casing; a detachable casing end cover mounting a bearing and formed to constitute an intake manifold; an exhaust manifold; a piston-operating cam in the chamber journaled in the bearing; a plurality of compressor units disposed about and without the casing each including a cylinder, a piston slideable within it, and valves operable thru movement of said piston; openings in the intake manifold thru which outside air may enter the cam chamber and pass with air within the chamber, which has been warmed by heat radiated from the compressor units, thru the valves; and means to convey air passing thru the valves to the exhaust manifold.

6. A compressor having in combination a casing; a cam chamber within the casing; a casing end cover mounting a bearing and formed to constitute an intake manifold; an opposite end cover mounting a bearing and formed to constitute an exhaust manifold, either or both of said covers being detachably secured to the casing; a piston-operating cam in the chamber journaled in the bearings; a plurality of compressor units disposed about and without the casing each including a cylinder, a piston slideable within it, and valves operable thru movement of said piston; openings in the intake manifold thru which outside air may enter the cam chamber and pass with air within the chamber, which has been warmed by heat radiated from the compressor units, thru the valves; and means to convey air passing thru the valves to the exhaust manifold.

7. A compressor having in combination a casing; a cam chamber within the casing; a casing cover mounting a bearing and formed to constitute an intake manifold; an opposite end cover 5 mounting a bearing and formed to constitute an exhaust manifold, either or both of said covers being detachably secured to the casing; a piston-operating cam in the chamber journaled in the bearings; a plurality of compressor units disposed about and without the casing each including a cylinder providing a compression chamber,

a piston slidable within it, and inlets to the compression chamber openable thru movement of said piston; openings in the intake manifold thru which outside air may enter the cam chamber and pass with air within the chamber, which 5 has been warmed by heat radiated from the compressor units, thru the inlets; and means to convey air passing thru the inlets to the exhaust manifold.
